UNITED STATES PATENT OFFICE.

CHARLES D. DURKEE, OF BROOKLYN, NEW YORK.

TAFFRAIL-LOG.

1,052,714.

Specification of Letters Patent. Patented Feb. 11, 1913.

Application filed March 21, 1911. Serial No. 616,947.

To all whom it may concern:

Be it known that I, CHARLES D. DURKEE, a citizen of the United States, and resident of Brooklyn, in the county of Kings and State of New York, have invented certain new and useful Improvements in Taffrail-Logs, of which the following is a specification.

This invention relates to ship's logs, used for measuring the speed of vessels and calculating the number of miles per hour at which the vessel is traveling.

The invention has special reference to that class of ships' logs which is known as taffrail logs, in which the measuring device is secured to the rail or other part of the stern of the boat, said measuring device being operated by a propeller on the end of a line trailing in the water from the stern 20 of the vessel.

The invention has for its object to provide an improved taffrail log which is simple in construction and which will effectively and accurately register the speed of 25 a vessel.

Referring to the accompanying drawing: Figure 1 is a view of a taffrail log constructed in accordance with this invention. Fig. 2 is a side view thereof with the registering mechanism disclosed, the casing thereof being partly broken away. Fig. 3 is a plan view in longitudinal section of the registering device and balance disk.

The taffrail log constructed in accordance 35 with this invention includes a registering device which may be of any suitable construction adapted for the use to which it is applied in connection with this invention.

To illustrate the manner of carrying out 40 the invention a particular form of registering device 1 is shown and described which consists of a metallic cylindrical casing 2, formed with a rear tubular projection 3, and a forward yoke 4 with a handle 5 having a 45 loop 6, to secure this registering device by means of a line to a rail or other part of the stern of a vessel. Said yoke 4 is swiveled to the casing 2 by means of pivot pins 7 on the sides of the casing. Mounted in the casing 2 is a number of rotary wheels 8, which are so geared together as to be successively 50 rotated. The periphery of each wheel 8 has thereon figures from 0 to 9 inclusive. Connected with the mechanism for successively 55 operating the wheel 8 is a rotary shaft 9 which extends through and projects from

the tubular projection 3. Secured in any suitable manner to the projecting end of the shaft 9 is a balance disk 10, having a tubular sleeve or projection 11, extending over the end of the shaft 9 and fastened thereto by a cotter pin 12. Mounted in the tubular projection 3, is a cylindrical support 13, through which the shaft 9 extends, said support 13 being formed with enlarged ends 14 containing raceways in which are located balls 15, the shaft 9 having a circular enlargement 16 which with one of the ends 14 of the support 13 forms a ball bearing and the several parts set forth forming ball bearings. Secured to the disk 10 in any suitable manner, as for example by a knot 17 in the sleeve 11, is one end of a line 18 of the usual length employed with a log, and secured to the other end of said line is a propeller 19 adapted with the line 18 to trail in the water astern of a vessel. The propeller 19 is formed with the stem 20 to which is secured the line 18, and with propeller blades 21 which are mounted on and project rearwardly from the stem 20, and are spaced apart from each other. The blades 21 are braced in any suitable manner, as for example by a ring 22 secured thereto and located between the blades 21 adjacent to their outer ends. By means of this construction a light and strong propeller is provided which will not sink so deep in the water as a more solid one.

The registering device may be made of brass or an alloy which will not rust.

The balance disk 10 serves as a steadiers and will cause the log to run more smoothly.

This invention is especially adapted to be used with motor boats.

The wheels 8 are located opposite an opening 23 in the side of the casing 2 exposing the numbers on the periphery of each wheel 8. The numbers on the wheel 8 at the extreme right read thousandths of a nautical mile or knot; those on the next wheel read hundredths; and those on the next wheel read tenths. For example the register 99,999 is ninety-nine and nine hundred and ninety-nine thousandths of nautical miles or knots. The next revolution of the registering device shows 00000 and continuing to rotate will start at 1 again and so on.

It will be observed that the handgrip portion of the handle 5 is formed of flat strip metal and the straight lengths of the same are

pressed in contact throughout their entire length and then riveted or otherwise rigidly fastened together so that accidental separation of the same is prevented. By this manner of forming the handgrip, the resistance to the passage of the instrument through the water is reduced, and at the same time, a small compact handgrip is provided that can be readily and firmly 10 grasped without danger of the parts thereof springing apart with the attendant danger of injury to the hands of the user.

It will also be observed that the rear end of the support 13 is in the form of a housing 15 in which the enlargement, or collar, 16, of shaft 9 is housed, and said collar by abutting the bearings 15, prevents forward longitudinal movement of said shaft. The forward end of support 13 is similarly provided with a housing, which may be enlarged, and a collar on shaft 19 is housed therein. The last-mentioned collar by abutting the forward end of support 13, prevents rearward longitudinal movement of the 25 shaft 9.

While a particular form of registering device has been shown and described any suitable registering device may be employed.

Having described the invention I claim.

30 1. A taffrail log comprising a casing provided with registering mechanism, and a

handle for the casing including a yoke formed of flat strip metal having its ends pivotally connected to opposite sides of the casing, its intermediate portions straight and in longitudinal contact throughout their lengths to form a handgrip, and its free portion shaped to form a line-engaging loop, and means for holding the straight portions of the yoke in rigid relation.

2. A ship's log comprising a casing open at its rear end and provided with a sight opening, registering mechanism in the casing and visible through the sight opening, a shaft extending through the casing and projecting beyond the open rear end thereof for operating the registering mechanism, a cylindrical support in the casing for the shaft and extending to the open rear end of the casing, said support being provided with forward and rear housings, collars on the shaft and lying within the housings, antifriction bearings in the housings and in contact with said collars, and means for rotating the shaft.

Signed at the city, county and State of New York this 6 day of March A. D. 1911.

CHARLES D. DURKEE.
